FABRIC

Lawrence Alexander Savage, Pelzer, S. C., assignor to The Kendall Company, Boston, Mass., a corporation of Massachusetts

Original application April 28, 1944, Serial No. 533,156. Divided and this application March 11, 1946, Serial No. 653,604

7 Claims. (Cl. 139—389)

1

The present invention relates to improvements in fabrics. The present application is a division of applicant's copending application Serial No. 533,156, filed April 28, 1944, now Patent No. 2,410,394, for Manufacture of textiles.

It is a principal object of the invention to produce a novel and improved fabric in which the angular relation of the filling yarns and the warp yarns is controlled to produce a distinctively new and useful structural characteristic of the woven fabric. Specifically, in accordance with the invention, it is proposed to vary the angular relation of successively woven filling picks to the warp, so that a recurring pattern of change in appearance and in the structural characteristics of the fabric is produced in the woven fabric. Such variation may be employed, for example, to produce a distinctive design characteristic in the fabric, or to cause the direction of successively added filling picks to conform with the outline or shape of the articles to be made from the fabric. Controlled variations in the angular relation of the filling and warp yarns may also be employed to impart an unusual strength characteristic to the fabric to increase the resistance of the fabric to stretch or failure from stresses exerted on the fabric in particular directions or with relation to some focal area of support.

With the above noted and other objects in view as may hereinafter appear, a feature of the invention consists in the construction and arrangement of a woven fabric having warp ends and filling picks of which filling picks along the length of the fabric are with respect to one another in different angular relations from the perpendicular to a line extending in the direction of the warp.

A preferred form of such fabric woven upon the loom illustrated and in accordance with the method described and claimed more particularly in applicant's copending application above referred to, may have the direction of the filling picks changed with relation to said perpendicular direction either abruptly or gradually and in accordance with any desired recurring pattern of change.

More specifically, a feature of the invention consists in the provision of a woven fabric of which the filling picks along the length of the fabric are gradually inclined first in one direction and then in the other direction from the perpendicular to a line extending warpwise of the fabric to form abutting fabric areas considered warpwise of the fabric in which the filling picks

2

are alternately in converging and diverging relation.

The invention is herein disclosed in a preferred form as embodied in a fabric adapted for use in the manufacture of cheese bandages of the general type described in the copending application of Ross C. Whitman, issued to Patent No. 2,396,905, dated March 19, 1946, for improvements in the Manufacture of textiles. In accordance with the teaching of that application, a fabric blank is woven consisting of a two-ply fabric having interwoven strip areas uniting the fabric plies so that by cutting along the interweaves, individual cheese bandages can be severed from the blank which when opened out are tubular in shape and ready for use.

In accordance with the present invention, a new and improved fabric for use in the manufacture of cheese bandages is produced in which the weft yarns forming the adjoining two-ply fabric areas are fanned out to form alternately converging and diverging fabric areas. The interwoven strip areas extending weftwise of the fabric interposed between and connecting together the two-ply fabric areas are woven with weft yarns which are inclined by a substantial amount from the perpendicular to the direction of the warp so that the strip areas are correspondingly inclined in alternately converging and diverging relation to one another.

The cheese bandages formed from a blank of this description by severing along the line of the interweave will when opened out have the shape of a truncated cone, the amount of taper depending upon the amount by which the weft yarns forming the interweaves are inclined from the perpendicular to the direction of the warp in the woven blank. In accordance with the invention, this useful characteristic of the woven fabric is produced without any necessity of employing the complicated harness and cam or jacquard controls which would ordinarily have been required for the weaving of such a pattern.

The fabric blank illustrated as embodying in a preferred form the several features of the invention, is woven with the apparatus and in accordance with the method described and claimed in applicant's copending application above referred to, of which this application is a division.

As indicated in Fig. 2 of the drawing, provision is made in the loom for controlling the warp in such a manner as to cause a temporary skew to be imparted to the warp ends passing through the heddles and reed supported by the lay, and thereafter when the filling picks have been woven

into the fabric to cause the warp to be returned to its normal position so that the filling picks appear in the finished fabric in positions inclined from the perpendicular to a line extending warpwise of the fabric. In order to produce the fabric shown in Figs. 1 and 2 of the drawings, in which a fan-like arrangement of the filling picks first in one and then in the other direction is produced, the amount and direction of the skew imparted to that portion of the warp passing through the loom is controlled to cause the warp to be skewed gradually first in one direction and then in the other direction in timed relation with the weaving and pattern control thereof, so that the successive interwoven strip areas will be placed in alternatively converging and diverging relation to one another.

The several novel features of applicant's improved fabric as herein described and claimed, will be readily understood by one skilled in the art from the following description taken in connection with the accompanying drawings, in which Fig. 1 is a somewhat diagrammatic view illustrating a portion of a fabric blank embodying in a preferred form the features of the invention; and Fig. 2 is a diagrammatic view in perspective illustrating one method of producing applicant's novel fabric on a loom.

The fabric blank illustrated in the drawing embodying in a preferred form the several features of the invention, comprises a two-ply fabric 10 produced by tubular weaving, and having at spaced intervals therein interwoven strip areas 12, 14, which extend transversely of the fabric alternately converging and diverging with relation to one another, and serve to divide the blank into bag-like sections from which individual cheese bandages are severed in their finished form ready for use. Whereas, in the copending application of Whitman above referred to, the interwoven strip areas extending obliquely across the blank are produced by the use of a relatively large number of harnesses and pattern means for controlling the same, the converging and diverging interwoven strip areas of the illustrated fabric blank are produced by controlling the angular relation of the warp ends and the filling picks, so that the filling picks in certain portions of the completed blank extend widthwise thereof in directions inclined from the perpendicular to a line extending warpwise of the fabric.

Figs. 1 and 2 disclose a fabric blank of which each transversely extending fabric section including the interwoven strip areas at each side thereof is constructed and arranged to comprise two cheese bandages placed end-to-end widthwise of the fabric. Each interwoven strip area 12 is inclined leftwardly across half the width of the fabric and then rightwardly across the remaining width of the fabric in accordance with the direction taken by the included filling picks. Each alternate interwoven strip area 14 is inclined rightwardly across half the width of the fabric and then leftwardly across the remaining width of the fabric. The disposition of the filling picks contained within each section of two-ply fabric between adjacent interwoven strip areas is such that these picks are relatively crowded together in the narrower portions of the fabric section and fan outwardly to form the wide portions of the fabric section.

It will be understood that a cheese bandage in accordance with the illustration of the Whitman application above referred to, is preferably composed of a loosely woven unbleached cotton

material of which the individual yarns may run between 20s and 50s in size. Substantial variation may appear in the weave, as any loose mesh material of this general type having the requisite strength circumferentially of the bandage may be employed. It is preferred, however, to employ fabric having a count which may run between 15 and 35 in the lengthwise direction of the bandage, that is, weftwise of the fabric, and between 30 and 50 in the transverse direction of the bandage, that is, warpwise of the fabric for each fabric ply.

In the illustrated form of blank produced in accordance with the invention, a relatively low count of filling picks, of the order of 20 to 30 to the inch, is employed in the weaving of each fabric ply contained between the interwoven strips 12, 14, and a substantially increased number of filling picks, of the order of 40 to 60 to the inch, may be employed in the weaving of the strip areas 12, 14. The blank has a relatively high count of warp ends which may be in the order of 40 ends to the inch. For purposes of illustration, it is assumed that each fabric ply will have a count of 40 warp ends to the inch and 20 filling picks to the inch. In the interwoven strip areas, the count of yarns in both directions is doubled by the inclusion of the yarns of both fabric plies so that there are 80 warp ends to the inch, and 40 filling picks to the inch. Preferably, however, the count of picks in the fill is still further increased to about 50 in the interweaves to insure a strong union of the fabric plies, although cases may arise in which a count of less than 40 picks is found desirable. The individual cheese bandages to be severed from the fabric blank are located in the blank with their longitudinal axes extending transversely thereof, so that the warp ends of the blank become the circumferentially extending yarns of the individual bandages and the filling yarns of the blank become the longitudinally extending yarns of the individual bandages.

The fabric blank herein disclosed is of advantage considered as a step product in the manufacture of cheese bandages, also in that the filling yarns forming each interwoven strip area of the fabric are all contained within the strip area throughout their length, so that the number of picks per inch within the interwoven strip area, may be substantially increased to still further strengthen the union between the fabric edges provided by the interweave without affecting the weave of the fabric plies forming the body portion of the individual bandages.

Fig. 2 of the drawings provides a somewhat fragmentary disclosure of a preferred form of apparatus and method for producing the fabric shown in this figure and in Fig. 1. This figure illustrates particularly the control of the warp as it is fed through a loom which may be of well known description, to produce a fabric in which the filling picks are inclined in varying degrees and in different directions from a vertical to the line of the warp to produce a recurring pattern of change along the length of the fabric as it is woven. It is assumed that the fabric is produced on a loom having mechanism for tubular weaving for the production of two-ply fabric, and pattern controls of ordinary description for changing the pattern of weaving to introduce interwoven strip areas extending weftwise across the fabric in accordance with a predetermined pattern of operation. The parts of the loom shown include a warp beam 20, a fabric

take-up roll 22, an idler roll 24 over which the warp ends are drawn from the beam 20, an idler roll 26 over which the woven fabric is drawn as it is woven, and two pairs of skew rods including rods 28, 30 pivoted intermediate their lengths and linked together for engagement with that portion of the fabric extending from the idler roll 26 to the fabric take-up roll 22, and including pivotally supported skew rods 32, 34 which engage with and are permitted to adjust themselves freely against that portion of the warp passing from the idler roller 24. The angular position of the skew rods 28, 30 is controlled positively from the pattern control mechanism of the loom by means of a downwardly extending link connection 36 with the outer end of skew rod 28. The two sets of skew rods 28, 30, and 32, 34 are located at opposite sides of the weaving apparatus consisting of the harnesses, lay and shuttle mechanism, which may be of ordinary description and are not here shown. A dot-and-dash line 38 indicates the approximate line of travel of the shuttle across the warp.

In order to produce the fabric specifically illustrated in Figs. 1 and 2, the skew rods 28, 30 are positively turned about their respective pivots by means of a pattern mechanism including the link connection 36 to cause that portion of the warp passing through the harnesses and lay to be gradually skewed or distorted during the weaving of the two-ply or tubular portion of the fabric, so that the filling picks are interwoven across the warp with individual warp ends which have been progressively advanced or retarded from their normal position with relation to one another. Subsequently, as the completed fabric leaves the loom, and prior to the winding onto the usual take-up roll, the fabric comprising the warp and the filling yarns interwoven therewith is skewed an equal amount in the opposite direction to cause the individual warp yarns to resume their normal positions with relation to one another. The filling yarns woven into the warp while in the skewed position, are caused by the latter return skewing operation of the warp to become inclined from the perpendicular to a line extending warpwise of the fabric. The skewing or distorting of that portion of the warp passing through the loom is gradually increased in accordance with a predetermined pattern of operation of the loom to reach a maximum amount at the same time that the pattern mechanism operates to discontinue the tubular weaving operation, and to initiate the interweaving of all of the warp yarns with the filling yarns to form an interwoven strip area across the width of the fabric. After an interwoven strip area which may, for example, be two inches in width, has been woven, the interweaving operation is discontinued, and tubular weaving is resumed. That portion of the warp passing through the loom is now gradually skewed in an opposite direction so that the individual warp yarns are returned to their normal relation. The skewing operation then continues until the warp has been skewed an equal amount in the opposite direction when the pattern mechanism again becomes operative to discontinue the tubular weaving and to start the weaving of another interwoven strip area. It will be understood that during this entire operation of skewing the warp, only that portion of the warp passing through the drop wires, harnesses and lay is skewed, and that the portion of the woven fabric leaving the loom is at

all times skewed by an equal amount in the opposite direction so that the individual warp yarns are returned to their normal relation before the fabric is wound upon the take-up roll. The pattern of operation above described is repeated, the warp being gradually shifted from one to the other skewed position during the weaving of each tubular or two-ply portion of the fabric, so that during the weaving of successive interwoven strip areas, the warp will be skewed a maximum amount first in one and then in the other direction. As will be evident from an inspection of Fig. 1 of the drawings, a distinctive fabric pattern is produced in which the interwoven strip areas are placed in alternately converging and diverging relation to one another, and in which the filling yarns tend to fan out from the narrower to the wider portions of the transverse fabric sections bounded by the successive interwoven strip areas.

While a fabric embodying the several features shown which are particularly adapted for the manufacture of cheese bandages, it will be understood that the invention in its broader aspects is not limited to the particular fabric shown or to a fabric adapted for this particular purpose. It is contemplated that fabrics may be woven which may, for example, be single ply, may be so woven that different fabric areas are formed with the filling yarns inclined in varying amounts but in one direction only from a perpendicular to a line extending warpwise of the fabric, and to fabrics in which such variation of inclination may be abrupt or not symmetrical. It is contemplated also that different fabric patterns may be employed lengthwise of the fabric which may require variations in the form of apparatus employed from that generally indicated in Fig. 2. While with the form of the invention illustrated, a relatively small fan-like variation in position of the filling yarns is employed, it is contemplated that such variations may be of substantially greater extent as, for example, for the manufacture of decorative fabrics where an extreme variation in the neighborhood of 45° from the vertical to a line warpwise of the fabric may be employed. It is contemplated further that fabrics may be manufactured in accordance with the invention in which the variation in position of the filling yarns may be employed to produce distinctive structural effects other than those produced in the particular form of the invention illustrated as, for example, to particularly strengthen the fabric at a focal point of stress. For this purpose, it will be evident that a fan-like arrangement of the filling yarns may be employed emanating from such a focal point.

The nature and scope of the invention having been indicated and a specific form of the invention having been described, what is claimed is:

1. A woven article for use as a cheese bandage having when opened out the shape of a truncated cone which comprises two fabric plies connected at their side edges by strip interwoven areas in diverging relation to one another of which the warp ends extend transversely about the bandage, and the filling picks extending longitudinally of the bandage are fanned out so that the filling picks forming the interwoven areas are contained within said areas throughout their length.

2. A woven article for use as a cheese bandage having when opened out the shape of a truncated cone which comprises two fabric plies connected at their side edges by strip interweaves in diverging relation to one another of which the warp ends which may have a count of in the or-

der of 30 to 50 to the inch for each fabric ply and 60 to 100 to the inch for the interweaves extend transversely about the bandage, and the filling picks extending longitudinally of the bandage which may have a count in the order of 20 to 30 to the inch for each ply and of 40 to 60 to the inch for the interweaves are fanned out so that the filling picks forming the interweaves are contained within the interweaves throughout their length.

3. A woven fabric comprising, with warp ends, adjacent groups of filling picks, having the picks of each group skewed in varying amounts with respect to the warp ends and interwoven therewith to form in said fabric a series of fabric areas, considered warpwise of the fabric, the filling picks of each succeeding area of the series being fanned out toward the opposite side of the fabric from the picks of the adjacent areas at each side thereof.

4. A woven fabric comprising, with warp ends, adjacent groups of filling picks, having the picks of each group skewed in varying amounts with respect to the warp ends and interwoven therewith to form in said fabric a series of adjacent fabric areas considered warpwise of the fabric, each succeeding area of the series being tapered toward the opposite side of the fabric from the adjacent areas at each side thereof.

5. A woven fabric comprising, with warp ends, adjacent groups of filling picks fanned out in opposite directions transversely of the warp to form a series of adjacent fabric areas considered warpwise of the fabric in which filling picks of each area are alternately in converging and diverging relation across the width of the fabric, said adjacent fabric areas being further arranged in complementary relation with that portion of each succeeding fabric area having the filling picks thereof in diverging relation toward one side of the fabric adjacent to that portion of the fabric areas at each side thereof having the filling picks thereof in converging relation toward the same side of the fabric.

6. A woven fabric blank as a step product in the

manufacture of cheese bandages comprising, with warp ends, adjacent groups of filling picks skewed with relation to the warp ends in varying amounts and interwoven therewith to form a series of adjacent tapered two-ply fabric areas considered warpwise of the fabric with interwoven single ply strip areas intervening between said two-ply fabric areas, each two-ply fabric area of the series being tapered toward the opposite side of the fabric from the adjacent two-ply fabric areas at each side thereof.

7. A woven fabric blank as a step product in the manufacture of cheese bandages comprising, with warp ends, adjacent groups of filling picks skewed with relation to the warp ends in varying amounts and interwoven therewith to form a series of adjacent tapered two-ply fabric areas considered warpwise of the fabric with interwoven single ply strip areas intervening between said two-ply fabric areas, each two-ply fabric area of the series having the filling picks thereof in alternately converging and diverging relation across the width of the fabric to form a two-ply fabric area tapered alternately in opposite directions across the width of the fabric, each succeeding two-ply area of the series being in complementary relation to the adjacent two-ply areas at each side thereof and having each tapered portion thereof adjacent to an oppositely tapered portion of said adjacent two-ply areas.
